Clifford R. Carney, Miami, Fla., assignor to Cellon Corporation, Miami, Fla., a corporation of Florida

Application August 8, 1945, Serial No. 609,526

6 Claims. (Cl. 62—108.5)

1

The present invention relates to ice tray grids and more particularly to ice tray grids which are removable from an ice tray, and which may be readily operated to secure the release of ice cubes therefrom.

The problem of freeing ice cubes from a tray in which they are frozen in a conventional type of mechanical refrigerator is one which has been long present in this art. The attempts to solve the problem have generally taken one of two directions. First, to provide a grid formed of a resilient material, such for example as rubber or the like, and which may be distorted to break the bond between the grid and the cubes, and thus to free the cubes from the grid. Second, to provide a grid having rigid partitioning members, certain of which are movable relative to other of the members for the purpose of breaking the adhesion between the ice cubes and the rigid elements of the grid construction. In both forms of such prior grids the grid mechanism and the ice when frozen presents a rigid mass in which the grid, whether resiliently flexible or whether mechanically united for movement of one rigid section relative to the other is locked rigidly in the ice block. In both types of grids there is a mechanical connection between the elements of the grid which imparts a structural strength to the grid member. When the ice is frozen therein the articulation of the grid elements is destroyed. In the case of the resilient type of grid, the resiliency of the material is much impaired and frequently lost at the low temperatures necessary for the freezing of the ice. The adhesion of the ice to the various portions of the rigid grid members in the type utilizing rigid members which are movable relative to one another, renders these grids immobile to the extent that they are for all practical purposes a rigid grid structure at the beginning of the ice removing operation. In order to satisfactorily break such grids from the ice cubes, it is necessary to apply a force thereto of sufficient magnitude to move one of the grid members relative to the other grid members, and having thus initiated the ice-freeing movement, to then follow it with the progressive movement of other of the grid members. This is frequently referred to in this art as a "progressive flow of power" through the grid.

As distinguished from previously known types of grids, the grid of the present invention is composed of a plurality of separate elements freely joined together in such a manner that a sudden force applied to any grid member is transmitted throughout the frozen grid and ice block to pro-

vide a fracturing of the ice block and the formation of cubes therefrom.

An object of the present invention is, therefore, to provide an ice tray grid structure having a plurality of grid members each being movable relative to the other grid members and loosely held in their assembled position by an elongated assembly pin.

A further object of the present invention is to provide an ice tray grid structure in which the longitudinal separator is formed of a plurality of independent articulated segments each of which is independently movable relative to the other segments forming the longitudinal member, and each of which is relatively movable relative to the cross-members.

A further object of the present invention is to provide an ice tray grid formed of a plurality of separate rigid elements so united in the assembled structure that each element is relatively movable with respect to the other elements making up the composite structure, and in which relative movement is initiated in the grid while frozen in an ice block by a downwardly directed blow, the shock of which is readily transmitted through the grid to the ice block as a whole, resulting in the fracture of the block and the ready release of the grid.

It is a further object of the present invention to provide an ice tray grid constructed of a plurality of separate rigid grid elements flexibly united for relative movement of any part relative to every other part in all directions, within predetermined limits whereby a shock transmitted to the grid while frozen in an ice block is readily transmitted throughout the entire frozen block and grid structure, resulting in the ready fracture of the ice block into a plurality of separate cubes, and the release of the grid structure therefrom.

Other objects of this invention will appear in the following description and appended claims, reference being had to the accompanying drawings forming a part of this specification wherein like reference characters designate corresponding parts in the several views.

In the drawings:

Fig. 1 is a perspective view with a portion broken away and showing an ice tray grid embodying the present invention.

Fig. 2 is a cross-section taken substantially on the line 2—2 of Fig. 1 in the direction of the arrows, and showing the grid structure prior to its placement in an ice pan shown in cross-section.

Fig. 3 is a cross-section similar to Fig. 2 but showing the grid in position in the pan.

Fig. 4 is a top plan of the grid shown in position in an ice pan.

Before explaining in detail the present invention it is to be understood that the invention is not limited in the application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The grid construction here shown comprises a plurality of transverse grid members each extending in one piece across the ice pan. In the space between the one piece transverse members 10 are provided transverse members formed of two L-shaped metal pieces 11 and 12 whose long arm forms a portion of a transverse spacer and whose short arms extend in opposite directions to provide segments of a longitudinal spacer member. One of the members 12 and one of the members 11 provide the first transverse grid member of the grid structure. The member 12 provides an end portion 13 which is shaped to conform to the internal contour of the ice pan for spacing the entire grid-structure within the pan. An end L-shaped spacer member 14 is provided at the opposite end of the grid structure to provide for spacing the grid structure from the opposite end of the pan. The separate parts are held together by an assembly pin 15 extending longitudinally through the pierced openings provided in the several separate elements forming the grid structure. The size of the pierced openings and the size of the assembly pin 15 are so selected that mechanical binding of the parts against relative movement is eliminated. Thus each of the separate units of the grid structure is free to move relative to other separate units of the grid structure as may be desired to the extent that play is permitted between the pierced openings and the longitudinally extending assembly pin.

If desired an enlarged striker plate portion 16 may be provided on one of the cross-members 12 and a striker plate 17 may be provided on the cross-members 10. It is to be understood, however, that such locations of the striker plates are merely suggestive and that various other locations may be used with equal success.

The grid of the present invention is placed in a tray 18 whose normal ice level is below the connections between the grid segments and the connecting pin 15. The grid may be separated from the pan and from the ice block, and the ice block broken into separate cubes by a shock resulting from a sharp impact or blow on any part of the grid structure, as all parts of the grid structure are loosely held in position by the connector pin 15.

In constructing a grid of the present invention, I prefer to use a heat transmitting material, such for example as sheeted aluminum alloys, magnesium alloys, or the like, the surfaces of which have been treated to render them non-adherent to water. One satisfactory method of accomplishing this is to subject the parts to treatment in an anodizing bath and thereafter to wax the anodized surfaces. Another satisfactory method is to polish the surfaces and thereafter to treat the polished surfaces with a water-proofing material such for example as a finish containing a water impermeable plastic substance in which silicon

has been substituted for carbon in the molecule. Such products are commercially known as "silicone" resins, and are available commercially under this name.

In order to separate the grid while frozen in the ice block from the pan 18, a sharp impact on the edge of the pan may be utilized to free the ice block and frozen grid therefrom, or the pan 18 may be heated as by placing under the water tap so as to free the block and the grid therefrom. In some instances I have found that the sharp impact on the vertically extending members 12 and 13 will be adequate, not only to free the grid from the frozen ice block, but also to free the grid and the block from the pan.

From the foregoing it will be understood that a grid construction embodying the present invention may be readily assembled from a plurality of parts, each of which may be separately fabricated. The parts are loosely held in their assembled relation so as to drop into position and occupy a predetermined position in the ice pan.

The present application is related to my co-pending applications Serial Numbers 609,524 and 609,525, filed August 8, 1945, on ice tray grid constructions.

I claim:

1. An ice tray grid including a plurality of unitary transverse members and a plurality of segmental transverse members each formed by one arm of a bent strip whose other arm extends substantially at right angles thereto and extends lengthwise of the central portion of the grid to form one segment of an articulated longitudinal divider member, and an assembly pin extending lengthwise of the grid through a pierced opening in each of said members for loosely connecting said unitary transverse members and said segmental transverse members.

2. An ice tray grid including a plurality of longitudinally spaced unitary cross members, and a plurality of loosely connected rigid grid members interposed between said unitary cross members and comprising a plurality of rigid members each of which comprises a bent strip forming a pair of arms extending substantially at right angles to each other, one of said arms extending lengthwise of the grid and abutting on one of said unitary cross members and forming one segment of an articulated longitudinal divider member and the other of said arms extending transversely of the grid on one side of said articulated longitudinal divider member.

3. An ice tray grid including a plurality of longitudinally spaced unitary cross members, and a plurality of loosely connected rigid grid members interposed between said unitary cross members and comprising a plurality of rigid members each of which comprises a bent strip forming a pair of arms extending substantially at right angles to each other, one of said arms extending lengthwise of the grid and abutting on one of said unitary cross members and forming one segment of an articulated longitudinal divider member and the other of said arms extending transversely of the grid on one side of said articulated longitudinal divider member, and an assembly pin extending longitudinally of the grid through aligned openings pierced in said rigid grid members and in said unitary cross members for loosely connecting said members.

4. A segmental grid for an ice tray and including a plurality of loosely joined rigid members each bent substantially at right angles to form one segment of an articulated longitudinal di-

vider member and one segment of a transverse partition member, a unitary cross member interposed between adjacent pairs of said rigid members and loosely connected therewith, and striker members located on the transverse partition segment of one of said rigid members and on the top edge of one of said unitary cross members to transmit the shock of a downwardly directed impact into said grid elements to effect movement thereof and the separation of ice therefrom.

5. An articulated grid for an ice tray and including an articulated longitudinal partition formed of a plurality of separate metal strips, each of which is bent substantially at right angles to form an extending arm lying on one side of said longitudinal partition, and comprising a portion of one transverse partition and a plurality of unitary transverse members interposed between the adjacent ends of the portions of said metal strips forming the articulated longitudinal partition, and an assembly pin extending on a line parallel to said articulated longitudinal partition and connected with said transverse members for

loosely joining said members in their assembled position.

5. An ice tray grid comprising a plurality of longitudinally spaced unitary transverse members, a segmental transverse member interposed between each pair of said unitary transverse members and having portions extending therefrom and forming segments of a longitudinal partition member, and a longitudinally extending connector member loosely connected with all of said transverse members.
